UNITED STATES PATENT OFFICE

2,263,111

HOUSING CONSTRUCTION FOR END CAR
BRAKES

Edwin E. Van Cleave, Chicago, Ill.

Application May 29, 1940, Serial No. 337,792

6 Claims. (Cl. 74—505)

This invention relates to housings for railway brakes, the moving parts of which correspond substantially to the construction disclosed by the patent to Naylor No. 2,174,668, granted October 3, 1939. It is the object of the invention to provide a new and improved form and arrangement of frame and enclosure means for supporting the working parts in position for smooth and easy operation, and for protecting the mechanism effectively from the weather for preventing any likelihood that ice will form or dirt accumulate at any point so as to make the brake hard to manage or slow or uncertain to respond under trying conditions of use.

In the improved arrangement as shown by the drawings illustrating the invention, the combination housing and framework comprises a main housing member in the form of a casting or a stamping pressed into form from heavy sheet metal, with a front plate portion formed integrally with side wall and top wall portions, the rear face of the housing member being closed by a back plate also in the form of a casting or a stamping. The main housing member is provided with means for supporting the front bearings for a plurality of shafts, and the back plate is provided with supporting means for the bearings for the lower two shafts, without the necessity for the provision of additional frame members. The rear bearings for the shafts located at the top portion of the brake mechanism, however, are supported by a single additional frame member which is in the form of a casting or a stamping shaped to fit snugly in the upper end portion of the main housing so as to be slidable readily into operative position therein, and shaped to fit snugly between the back plate and portions of the main housing so as to be held strongly in operative position by engagement with the housing parts when the housing is assembled without the necessity for being secured in position in any way other than by its being enclosed in the housing.

In a modified construction as also illustrated, the rear bearings for all of the operating mechanism are supported from an inserted frame member of the type described, the bearings for the lower shafts being supported by an arm formed integrally with the top plate portion and extending downwardly therefrom so as to be held rigidly in position thereby.

It is another object of this invention to improve constructions of this type in sundry details hereinafter pointed out. The preferred means by which the several objects have been

attained are illustrated in the accompanying drawings, in which—

Fig. 1 is a front face view of the improved brake, with the greater portion of the operating wheel and a part of the front wall of the housing broken away for clearness of illustration;

Fig. 2 is a vertical cross sectional view taken substantially at the line 2—2 of Fig. 1 but with additional portions of the operating wheel shown;

Fig. 3 is a horizontal sectional view through the housing and frame member taken substantially at the line 3—3 of Fig. 1;

Fig. 4 is a top plan view of the frame member enclosed by the housing as shown in Fig. 3;

Fig. 5 is a front face view of the frame member shown in Fig. 4;

Fig. 6 is a horizontal sectional view taken substantially at the line 6—6 of Fig. 1;

Fig. 7 is a central vertical sectional view through a modified form of frame plate with portions of associated parts; and

Fig. 8 is a front face view of the frame plate shown in Fig. 7.

Referring now to Figs. 1 to 6, inclusive, of the drawings, in which corresponding parts are indicated by the same reference characters, 10 indicates a housing member comprising a front plate 11, side plate portions 12, and a top plate portion 13, the several plate portions being formed integrally with each other by a casting operation in the arrangement shown. At the rear edge portions of the side plates 12 and the top plate 13, a rear plate 14 is provided serving to close the housing member 10 except for the opening at the bottom of the housing. The plate 14 also is in the form of a casting, but it will be understood that the two housing members 10 and 14 might be formed otherwise than by casting if it should be so desired.

As is best shown in Figs. 1 and 6, the side plates 12 are bowed inwardly at 15 at opposite sides of the housing so as to provide two upwardly facing bearings or shoulders 16 at the same level at opposite sides of the housing. The side wall portions are also bowed inwardly at 17 at their lower end portions. At the inwardly bowed portions of the side walls, the back plate 14 is brought into face to face engagement with a portion of the wall of the housing member 10, at which points the two housing members are secured rigidly together by means of rivets 18 (see Fig. 1).

The operating mechanism of the brake com-

prises an operating shaft 19 journaled between the front plate 11 and the rear plate 14, such shaft 19 having fixedly mounted thereon a ratchet wheel 20 and a pinion 21. The pinion 21 is in mesh with a gear 22 carried by a winding sheave 23 journaled between the plates 11 and 14. A chain 24 is secured to the gear 22 and the sheave 23 by means comprising a pin 25 so that upon rotation of the gear the chain 24 is wound about the sheave 23. A pin or lug 26 is mounted upon the sheave 23 in position to engage one of the links of the chain 24, as is clearly shown in Fig. 1. A hand wheel 27 is fixedly mounted on the front end of the shaft 19 in front of the housing member 10, as is best shown in Fig. 2.

In the upper end portion of the housing 10, a plurality of shafts or pins 28, 29 and 30 are rigidly mounted, such shafts having their forward ends supported by bearings 31, 32 and 33, respectively, carried by the front plate 11 (see Fig. 3). For supporting the rear end portions of the shafts 28, 29 and 30, a transverse frame plate 34 in the form of a cross bar is provided, slidably mounted in the upper end portion of the housing, resting at its ends upon the upwardly facing bearings 16 in the side wall portions 12 of the housing member 10. As is clearly shown in Fig. 3, the transverse frame plate 34 is provided with bearings 35, 36 and 37, directly opposite to the bearings 31, 32 and 33, respectively. As is best shown in Fig. 1, the frame plate 34 is of such size and shape as to fit snugly between the side plates 12, being positioned between the bearings 16 formed by the side plates and the obliquely disposed portions of the casing at its upper end whereby the plate is held firmly against movement either vertically or transversely. As is best shown in Fig. 3, the end portions of the transverse frame plate 34 stand in engagement with lugs 38 formed on the casing at its opposite sides, such lugs serving to hold the frame plate pressed firmly against the rear plate 14, as is clearly shown in Figs. 2 and 3. In the arrangement shown, the frame plate 34 is in the form of a channel.

As is best indicated in Fig. 1, the shaft 28 is provided with a pawl 39 provided with a counter-weight 40 thereon adapted normally to hold the pawl out of engagement with the ratchet wheel 20. The pin or shaft 30 in turn is provided with a weighted arm 41 which is in position to engage the top face of the pawl 39 for forcing it into engagement with the ratchet wheel 20. The shaft 29 is provided with a controlling member comprising a lug 42 positioned in a recess 43 in the weighted arm 41 whereby rotary movement of the shaft 29 serves to control the position of the weighted arm with respect to the pawl 39.

In the construction illustrated, the shaft 29 extends forwardly through the front plate 11 of the housing, being provided on its outer end with a handle or lever 44 for giving the shaft the desired rotary movement. A spring washer 45 is mounted between the transverse frame plate 34 and a suitable bearing portion on the shaft 29 (not shown) for providing a frictional grip upon the shaft whereby the shaft is held yieldingly against rotary movement from any position to which it is turned. At its rear end, the shaft 29 is provided with a cotter pin 46 which holds a washer 47 in position against the bearing 36 of the transverse frame plate 34 for insuring that the frictionally acting means shall be effective for controlling the movement of the shaft 29.

Inasmuch as the pawl 39 with its counter-

weight 40 operates under the control of the weighted arm 41 and the controlling means comprising the shaft 29 and the handle 44 in the same manner as is described in said earlier Naylor patent, it is believed to be unnecessary to describe the same further herein.

By the use of the improved construction as above described, the combination housing and frame parts are made very effective from the standpoint of the operation of the brake and also from the standpoint of providing an enclosure for the protection of the working parts. The arrangement is such that the parts can be very easily and cheaply produced and easily assembled. With the transverse frame plate 34 slidably fitted in the upper end of the housing so as to be held against movement either vertically or sideways as above described, it is unnecessary that any means be provided for holding said frame plate in position other than through the medium of the housing parts provided with the spacing lugs 38. In the assembly of the parts, the shafts 28, 29 and 30 are slipped into position in the bearings carried by the housing member 10, together with the interfitting parts carried thereby, after which the plate 34 is slid into place and the pin 46 is inserted through the shaft 29 so as to hold the spring washer 45 compressed. The arrangement is such that the parts go very quickly and easily into their designed positions and such that the parts are held in position by engagement with the back plate 14.

In the construction shown in Figs. 7 and 8, a modified form of frame plate is shown corresponding to the frame plate 34 of the arrangement first described. As is best shown in Fig. 8, the modified frame plate comprises a cross bar portion 48 in the form of a casting having an arm 49 extending downwardly therefrom at its central portion. The cross bar portion 48 is provided with bearings 50, 51 and 52 corresponding with the bearings 35, 36 and 37 of the plate 34, the cross bar portion 48 being of the same size and shape as the plate 34 so as to be held rigidly in position in the upper end portion of the housing in the same manner as is above described in connection with the plate 34. As is clearly shown in Fig. 7, the arm 49 is offset rearwardly with respect to the cross bar portion 48 so as to extend downwardly at the rear face of the housing, such arm being provided with bearings 53 and 54 for supporting the rear ends of the shafts 19 and 23 respectively. The arm 49 is provided with a strengthening rib 55 between the bearings 53 and 54 and with a second strengthening rib 56 about its outer edge portion, such ribs 55 and 56 being located on the front face of the plate. The cross bar portion 48 is provided with a strengthening rib 57 at its rear face about the outer edge portions of the bar. At its lower end, the arm 49 is provided with obliquely extending lugs 58 adapted to engage the shoulders at 17 in the side plate portions 12 for bracing the arm more strongly in position.

By the use of this modified form of frame plate member, I am enabled to use a substantially plain straight back plate member 59 in lieu of the slightly different form of back plate as shown in Fig. 2 arranged for supporting the bearings for the shafts 19 and 23. By the use of the modified arrangement, the assembly of the brake and housing is simplified, since the frame plate can be connected in operative position in the front housing member for holding the operating parts in their final working positions before the

back plate 59 is placed in position to close the rear face of the housing.

While the arrangement as above described is preferred, it is to be understood that the invention is not limited specifically thereto except so far as the claims may be so limited, it being understood that changes might well be made in the form and arrangement of the parts without departing from the spirit of the invention.

I claim:

1. In a hand brake structure for railway cars, the combination of a housing member comprising a face plate and top and side plate portions rigidly connected together in unit form, a second face plate secured to said unit housing member opposite to said first-named plate portion so as to form a housing therewith, operating parts for said brake rotatably supported at one face of the housing by one of said face plate portions, and means for rotatably supporting said operating parts at the opposite face of the housing comprising a frame plate having a snug sliding fit in a portion of said unit housing member so as to be held rigidly in position by engagement with the assembled housing members.

2. In a hand brake structure for railway cars, the combination of a housing member comprising a face plate and top and side plate portions rigidly connected together in unit form, a second face plate secured to said unit housing member opposite to said first-named plate portion so as to form a housing therewith, operating parts for said brake rotatably supported at one face of the housing by one of said face plate portions, and means for rotatably supporting said operating parts at the opposite face of the housing comprising a frame plate slidably supported in said unit housing member by means of a cross bar portion extending across the upper end part of the housing and engaging upwardly facing bearings provided by the housing so as to be held rigidly in position by engagement with the assembled housing members.

3. In a hand brake structure for railway cars, the combination of a front housing member in the form of a casting comprising a front plate and top and side plate portions, a back plate member for closing the rear face of said housing member, operating parts for said brake rotatably supported in front by said front plate portion of the housing, and means for rotatably supporting said operating parts at the back comprising a frame plate having a portion thereof in snug fitting engagement inside of a portion of the cast housing member so as to be held thereby rigidly against movement vertically or transversely and held rigidly by engagement with the back plate from movement forwardly or backwardly with respect to the housing member.

4. In a hand brake structure for railway cars, the combination of a front housing member com-

prising a front plate and top and side plate portions rigidly connected into unit form therewith, a back plate member for closing the rear face of said front housing member, operating parts for said brake comprising a ratchet wheel and a pawl in cooperative holding relation thereto rotatably supported in front by said front plate portion of the housing, bearing means for rotatably supporting said ratchet wheel and said

10 pawl at the rear face of the housing comprising a bearing for at least said pawl carried by a frame plate slidably mounted in the upper end portion of the housing and fitting snugly therein so as to be held against movement either vertically or transversely, and lugs carried by said housing member adapted by engagement with said frame plate to press said frame plate rigidly against said back plate so as to be held firmly in position in the housing.

20 5. In a hand brake structure for railway cars, the combination of a housing member comprising a face plate and top and side plate portions rigidly connected together in unit form, a second face plate secured to said unit housing member opposite to said first-named plate portion so as to form a housing therewith, operating parts for

25 said brake rotatably supported at one face of the housing by one of said face plate portions, and means for rotatably supporting said operating parts at the opposite face of the housing, comprising a frame plate slidably supported in said unit housing member by means of a cross bar portion extending across the upper end part of the housing and engaging upwardly facing 30 bearings provided by the housing so as to be held rigidly in position by engagement with the assembled housing members, and an arm extending downwardly from said cross bar portion in fixed 35 position with respect thereto for assisting in the support of said operating parts.

40 6. In a hand brake structure for railway cars, the combination of two housing members cooperating to form a housing and comprising spaced front plate and back plate portions, a frame plate 45 slidably mounted in the housing so as to be held rigidly in position therein by engagement with the assembled housing members, a winding sheave rotatably supported by said front plate portion of the housing and by said frame plate, a ratchet 50 wheel rotatably supported by said front plate portion of the housing and by said frame plate, means operatively connecting said ratchet wheel with said winding sheave for causing said parts to rotate in unison, and a pawl rotatably supported by said front plate portion of the housing and by said frame plate in position for operative 55 engagement with said ratchet wheel for holding the ratchet wheel normally against rotation in one direction.

EDWIN E. VAN CLEAVE.
